UNITED STATES PATENT OFFICE

2,269,175

ELASTIC FLUID TURBINE

David J. Bloomberg, Newton, Mass., assignor to
General Electric Company, a corporation of
New York

Application December 8, 1939, Serial No. 308,158

4 Claims. (Cl. 253—69)

The present invention relates to elastic fluid turbines, particularly of the type which include a first stage with a bucket wheel having at least two axially spaced rows of buckets although it is not necessarily limited thereto. In certain cases, such as where turbines are used for ship propulsion, they are subject to considerable speed variation. In such cases two essentially different operating conditions may occur, one condition at cruising speeds with a large first stage pressure ratio and low wheel speed and the other condition with a low first stage pressure ratio and a high wheel speed. From a design standpoint, the first condition can best be satisfied by a first stage bucket wheel having at least two axially spaced rows of buckets, whereas the second condition calls for a single row wheel.

The object of my invention is to provide an improved construction and arrangement of elastic fluid turbines subject to both conditions aforementioned which may be efficiently and economically operated. This is accomplished in accordance with my invention by the provision of a bucket wheel or wheels having several rows of buckets and a device for by-passing elastic fluid discharged from a section of the first row with regard to the other row or rows of buckets. The elastic fluid bypassed with regard to the other rows of buckets is conducted directly to a lower stage. With such an arrangement more than 10% improvement in cruising economy, that is during low speed operation, may be attained at a sacrifice of only 1% of maximum speed economy.

For a better understanding of what I believe to be novel and my invention, attention is directed to the following description and the claims appended thereto in connection with the accompanying drawing.

In the drawing Fig. 1 is a sectional view of an elastic fluid turbine embodying my invention; Fig. 2 is a section along lines 2—2 of Fig. 1; and Fig. 3 is a section along lines 3—3 of Fig. 1.

The turbine arrangement comprises an outer casing 10 including a solid rotor forming a shaft 11 with a first stage bucket wheel 12 and a second stage bucket wheel 13. Elastic fluid is conducted to the turbine through a valve chest 14 forming chambers 15, 16 and 17 communicating with separate sections of a first stage nozzle plate 18 supported on the casing 10. The flow to the chambers 15, 16, 17 is controlled by valve means 19. During low or cruising speed operation the valve 19 for the chamber 15 is opened while the valves for chambers 16 and 17 are closed and,

vice versa, during high speed operation the valve 19 for chamber 15 is closed and the valves 19 for chambers 16 and 17 are opened.

The first bucket wheel 12 has two complete rows of buckets 20 and 21. According to my invention I provide means whereby a portion of the elastic fluid discharged from the row of buckets 20 is conducted to the row of buckets 21 and another portion of the elastic fluid discharged from the row of buckets 20 is bypassed with regard to the row of buckets 21 and conducted directly to a lower stage, in the present instance the second stage, including the aforementioned wheel 13 and a nozzle diaphragm 22. To this end I provide an intermediate nozzle plate 23 between the two rows of buckets 20, 21 in alignment with that section of the first row of buckets 20 which receives elastic fluid from the first chamber 15. In the present instance the intermediate nozzle plate 23 extends over an arc of approximately 30°. The intermediate nozzle plate 23 is suitably supported on the outer casing 10. Thus, the elastic fluid discharged from the chamber 15 of the valve chest first passes through the first row of buckets 20 and is then properly directed by the intermediate nozzle plate 23 to the second row of buckets to be discharged therefrom into the second stage.

The elastic fluid discharged from the valve chest chambers 16, 17 passes through the first row of buckets and thereafter is bypassed with regard to the second row of buckets 21. This is accomplished by shielding and guiding devices 24 and 25, each extending over an arc corresponding to the arcs of supply from the chambers 16 and 17. Each device has an outer wall 26 secured to webs 27 by means of screws 28 and side walls 29 and 30 respectively located on opposite sides of the row of buckets 21, both walls 29 acting as shields to prevent passage of elastic fluid through the row of buckets 21. The side wall 29 which is located between the two rows of buckets 20, 21 is curved smoothly to deflect and guide the elastic fluid discharged from the first row of buckets 20. Guiding of the elastic fluid is further improved by the provision of a row of guiding vanes 31 secured to the curved wall 29 adjacent the row of buckets 20. The vanes 31 in the present instance are inclined about 45° to the direction of elastic fluid discharged from the row of buckets 20.

During operation elastic fluid is supplied from the chamber 15 and passed through the two rows of buckets 20 and 21 during cruising condition and elastic fluid is supplied from the chambers

16, 17 during high speed condition. The elastic fluid supplied from the chambers 16 and 17 is passed through the first row of buckets 20 and bypassed with regard to the second row of buckets 21.

What I claim as new and desire to secure by Letters Patent of the United States is:

1. Elastic fluid turbine comprising a casing, first stage wheel means with at least two axially spaced rows of buckets, means for conducting elastic fluid to the first row of buckets, an intermediate nozzle plate for directing elastic fluid discharged from a section of the first row to a section of the second row, and a shielding and guiding device for bypassing elastic fluid discharged from another section of the first row with regard to another section of the second row and to prevent the flow of fluid through the other section of the second row, said device being supported on the casing and having a curved wall disposed between the two rows of buckets, and another wall adjacent the outlet side of the other section of the second row.

2. Elastic fluid turbine comprising first stage wheel means with at least two axially spaced rows of buckets, means including a nozzle plate for conducting elastic fluid to the first row of buckets, an intermediate nozzle plate for directing elastic fluid discharged from a section of the first row to a section of the second row, and a shielding and guiding device for bypassing elastic fluid discharged from another section of the first row with regard to another section of the second row and to prevent the flow of fluid through said other section of the second row, said device enclosing both sides of a section of the second row of buckets and having a curved wall between the two rows of buckets and a plurality of directing vanes secured to the curved wall adjacent the first row of buckets.

3. Elastic fluid turbine comprising a casing, a

first stage nozzle plate, a valve chest forming separate chambers for conducting elastic fluid to two separate sections of the nozzle plate, first stage bucket wheel means having axially spaced first and second rows of buckets, the first row being arranged to receive elastic fluid issued from both sections of the nozzle plate, an intermediate nozzle plate between the two rows of buckets for conducting a portion of elastic fluid issued from one section of the first row to the second row, and a device detachably supported on and spaced from the casing to define a channel therewith, the device having walls enclosing and shielding a section of the second row to prevent the flow of fluid therethrough and to bypass fluid discharged from the first row with regard to the second row, one of said walls being curved and having guide vanes to form a smooth passage for the bypassed fluid.

4. Elastic fluid turbine comprising a casing, a bucket wheel located in the casing and having a first and a second row of buckets, means for conducting elastic fluid to the first row of buckets, nozzle means located between the two rows of buckets for conducting elastic fluid discharged from a section of the first row to a section of the second row, means for bypassing substantially all of the elastic fluid discharged from another section of the first row with regard to the second row, said means comprising a segmental channel member having walls on opposite sides of the second row and defining with the casing a bypass channel, one of said walls being located between the two rows of buckets and having guide vanes adjacent the first row of buckets to conduct fluid discharged from the other section of said first row into said bypass channel, and another bucket wheel arranged to receive fluid conducted through the bypass.

DAVID J. BLOOMBERG.
